UNITED STATES PATENT OFFICE

JESS F. MORRISON, OF DUNHAM, KENTUCKY

TROLLEY-WIRE GUARD

Application filed September 14, 1928. Serial No. 305,999.

The present invention relates to improvements in guards for use in mines, to give protection against contact with the trolley wire or other charged conductor.

One of the important objects of the present invention is to provide a trolley wire guard of the above mentioned character that can be readily and easily attached to the hangers used in supporting the trolley wire from the roof of the mine without necessitating any alterations.

Still a further object is to provide a trolley wire guard of the above mentioned character which is simple in construction, inexpensive, strong and durable, and further well adapted to the purpose for which it is designed.

Other objects of the invention will become apparent as the nature of the invention proceeds and when taken in connection with the accompanying drawings.

In the accompanying drawings; forming a part of this application, and wherein like reference characters designate like parts throughout the several views:

Figure 1 is a side elevation of a trolley wire guard embodying my invention, showing the same attached to a hanger and suspended from the mine roof.

Figure 2 is a top plan view of the guard per se.

Figure 3 is a sectional view, taken approximately on the line 3-3 of Figure 2.

Figure 4 is a longitudinal sectional view taken substantially upon the line 4-4 of Figure 2, and

Figure 5 is a detail perspective view of one of the reinforcing strips associated with each of the side boards constituting the guards per se.

In the drawings, wherein for the purpose of illustration is shown the preferred embodiment of my invention, the numeral 1 designates a conventional hanger that is suspended from the roof of a mine, and connected to the bottom of the hanger in the usual manner is the trolley wire 2, the clamping means for the trolley wire which is associated with the hanger 1 being illustrated at 3, in Figure 3.

The circular rim portion that extends around

the bottom of the hanger body is indicated at 4.

My improved guard comprises the side boards 5 and 6 that constitute the guards per se, these side boards being adapted to extend for the full length of the trolley wire, and it is of course understood that the side boards are constructed in section, one section being preferably of such length as to extend a considerable distance and any appropriate means may be provided for securing the adjacent ends of the sections of the side boards together.

My guard further includes the provision of a particular means for mounting the guard board on the trolley wire hangers and to this end, there is provided a pair of bolts 7 and 8, respectively, that extend transversely through suitable openings provided therefor in the opposed side boards 5 and 6, adjacent the upper edge thereof and on opposite sides of the hanger 1. These bolts also project through reinforcing strips 9 that are secured on the inner and outer faces of each side board by the fastening means illustrated at 10. The ends of each bolt are threaded for receiving thereon the clamping nuts 11.

The bracket structures further provision of the opposed arcuate shaped jaw members 12 and 13, each of which is of identical construction and the inner face of each jaw is provided with a groove to fit the rim portion 4 of the hanger 1, in the manner as clearly disclosed in Figures 3 and 4 of the drawings. These complementary jaw members enclose a considerable portion of the rim 4.

Outwardly extending arms 15 and 16 are formed on the respective end portions of each jaw member. A relatively small apertured lug 17 is formed on the end of each of the arms 15, while larger apertured lugs 18 are formed on the outer ends of the arms 16 and as is clearly indicated in Figure 2, the arms 16 of the opposed jaw members are arranged in diagonally opposed relation with respect to each other and obviously the arm members 15 are also arranged in diagonally opposed relation. The lugs 17 and 18 are slidable on the respective bolts between the guide boards 5.

In order to further brace the guide boards, each arcuate shaped jaw member is formed at its central portion on the outer face thereof with a boss 19, which is engaged by the respective side boards when the parts are properly adjusted.

When the guard boards 5 and 6 are properly positioned on opposite sides of the conductor member 2 and the jaw members are tightly gripped around the rim portion 4 and held in this manner by means of the nut 11, it will be observed that the lower edges of the side boards extend considerably below the conductor wire 2, and therefore any object passing beneath the trolley wire will be prevented from engaging therewith.

The simplicity of my improved guard enables the same to be readily and easily installed and will not necessitate any alteration 20 of the trolley wire hangers with which said guard is associated.

Furthermore, my trolley wire guard will at all times be positive and efficient in carrying out the purposes for which it is designed 25 and the necessary adjustments can be made readily and easily. A structure of this character will furthermore be strong and durable and yet inexpensive.

While I have shown the preferred embodiment of my invention, it is to be understood that various changes in the size, shape and arrangement of parts may be resorted to, without departing from the spirit of the invention or the scope of the appended claim.

35 I claim:

A trolley wire guard comprising a pair of opposed arcuate straight jaws adapted to grip the rim portions of a trolley hanger therebetween, said jaws being provided at 40 their respective ends with a pair of laterally extending arms and rearwardly disposed lugs formed integral with the arms adjacent their respective outer ends to provide slide bearings, the lugs of one pair of diagonally disposed arms being considerably longer than the lugs of the other pair of arms, a bolt 45 extending through and beyond each pair of opposing lugs of the said jaws and having its opposite end threaded, a pair of spaced 50 guard boards respectively mounted on corresponding threaded ends of the bolts, and a pair of clamping members on each threaded end of the bolt and engaging opposite faces of a guard board.

55 In testimony whereof I affix my signature.
JESS F. MORRISON.
